UNITED STATES PATENT OFFICE.

HENRY K. EILERS, OF PLAINFIELD, NEW JERSEY, ASSIGNOR TO PYRAMID IRON PRODUCTS CORPORATION, A CORPORATION OF NEW YORK.

GRATE BAR.

Application filed March 16, 1927. Serial No. 175,767.

The invention relates more particularly to an improved grate bar to be used in the fire boxes of boilers, furnaces and the like, to facilitate the use of small sizes of anthracite 5 coal or fine bituminous coal so as to obtain satisfactory and efficient results therefrom, thereby reducing the cost of operation.

Grate bars of various kinds for the use of this type of coal have been in use for some 10 time, but such grate bars, in some cases, have been provided with a plurality of separated caps, cast integral with the body of the bar, and located over single vertical air passages, opening respectively through a plurality of 15 horizontal air passages into grooves or channels surrounding the individual caps covering the respective vertical air passages. In grate bars of this type, it frequently happens, in practice, that any irregular expansion or 20 contraction of the caps or grate bars is liable to crack the individual caps or the integral supporting members holding the caps to the body portion of the bar. When this occurs, the caps, so affected, may be destroyed 25 or entirely broken away, thereby decreasing the usefulness of the grate bar, and ultimately requiring replacement, either of the caps or the entire bar.

An improved grate bar with more rigid 30 connections between the caps and the body of the grate bar, but wherein single caps cover only a single vertical air passage is shown in the Eiler et al. Patent No. 1,585,967 of May 25, 1926, and the present grate bar is an improvement thereon. The primary object in 35 my present improvement, as hereinafter described, is to provide a grate bar with a more rigid construction, wherein continuous elongated caps, spaced apart laterally, are adapted 40 to provide continuous longitudinal channels or passages therebetween. Separated vertical air passages under each flange of the elongated caps communicate by lateral or horizontal passages with the respective continuous channels between the caps, the entire structure being braced in both directions by a plurality of longitudinal ribs and transverse 45 partitions. As pointed out later, these ribs and partitions are adapted to define and separate the vertical-horizontal air passages leading 50 to the continuous channels or passages between the elongated caps.

A further object, therefore, is to provide a plurality of vertical air passages, separated

by longitudinal ribs, which are provided with 55 lateral flanges along their upper edges, giving them a T-shape in cross section, the T-shaped ribs being located on two levels, such that the lateral flanges or T-heads of the ribs on the upper level, which form the caps, overlap or extend beyond the edges of the T-flanges on the ribs of the lower level, the respective flanges on the two levels being spaced vertically, so as to provide horizontal or lateral 60 passages leading from the respective vertical 65 passages, (one on each side of the mid rib or stem of the T) under the caps to the continuous 70 passages therebetween. By this construction, it will be seen that each vertical passage is provided with but a single lateral 75 passage opening into the continuous passage between the caps.

A further object is to provide a plurality 80 of transverse integral partitions for rigidly 85 bracing the longitudinal ribs and the flanges forming the caps on the upper level, so that there is little possibility of the caps being cracked or broken away by unequal heat 90 conditions during combustion, or unequal expansion and contraction of the grate bars. Obviously, such a construction lends 95 itself to the formation of a plurality of vertical air passages separated by the partitions and the longitudinal ribs, there being two series of such vertical-horizontal 100 air passages under the caps, opening respectively into the continuous channels or air passages on opposite sides of the caps, thereby overcoming objections, which might be raised to the use of a single vertical passage for supplying air through a plurality of lateral openings under individual caps.

One form and adaptation of my improved 105 grate bar is shown in the accompanying drawings, in which Fig. 1 shows a top plan view of the grate bar; Fig. 2 represents a vertical longitudinal section of the grate bar on the line 2-2 of Fig. 4 and along an irregular line 2-2 of Fig. 3; Fig. 3 shows a plan view of the underside of the grate bar and Fig. 4 is a transverse section on the line 4-4 of Fig. 2.

Referring to the drawings, it will be seen 110 that, in the present instance, my improved grate bar comprises a body portion 1 of elongated rectangular shape, preferably provided with depending lugs 2, at each side thereof, for supporting the individual grate

bar sections in position in the fire box of a furnace or boiler. It is preferable to use a plurality of sections, like those shown in Fig. 1 and when so used, adjoining sections 5 may be made to overlap by providing the individual grate bars with a flange 3, upon which the end 4 of the adjoining grate bar may rest.

In my improved grate bar, a plurality of 10 parallel ribs 4 and 5 are cast integrally with and extend longitudinally of the body 1, the ribs being provided with outwardly projecting flanges along their upper edges, so that the cross section is substantially T-shaped, 15 as shown in Fig. 4. The longitudinal ribs 4 and 5 are arranged on two levels, as shown in Fig. 4, particularly as to the T-heads or lateral flanges along their upper edges. The ribs 4, with flanges on the upper level, are 20 provided with slightly wider T-flanges 6, which are preferably flattened on top and form elongated caps, as shown in Figs. 1 and 4. The T-shaped ribs 4 alternate with the ribs 5 and are spaced from each other 25 to provide continuous longitudinal channels or passages 7 therebetween. The bottoms of the channels or long narrow air passages between the caps 6 are formed and determined by the flanges 8 of the T-heads on the ribs 5, 30 on the lower level.

The ribs 4 and 5 are spaced from each other laterally, so as to provide vertical air passages 9 on each side of the ribs 4 which extend along the middle of the caps 6. The 35 T-shaped ribs 4 and 5, being on different levels, as previously pointed out, are also spaced apart vertically, so as to provide transverse or horizontal passages 10, as continuations of the vertical passages 9, the horizontal passages communicating with the continuous longitudinal channels or passages 7, as will be seen in Fig. 4. It will thus be seen that air entering the vertical passages 9 will 40 pass upward therethrough and then laterally through the horizontal or transverse passages 10, into the channels 7, which lie between the caps 6, over which the coal is adapted to be spread, the long narrow channels 7 giving 45 the air access to the coal for efficient combustion thereof.

To facilitate the passage of the air from 50 below the grate bar, into the channels 7 between the caps 6, the T-flanges 11 of the ribs 5 on the lower level are preferably beveled on their upper faces at 12, so as to slope in opposite directions from the middle and thereby deflect and facilitate the passage 55 of air. Also, in order to eliminate dead air pockets and further strengthen the caps 6, the corners 13 between the vertical and horizontal portions of the T-shape ribs 4 are rounded, 60 as will be seen in Fig. 4.

It has been previously pointed out that 65 the caps in grate bars provided with air passages under individual caps, and intended

for use with small sizes or fine coals, are liable to become broken away or cracked, therefore, it will be understood that, in the present instance, the caps 6 are materially strengthened by being formed as continuous longitudinal caps, extending from end to end of the grate bar section, and these caps are still further strengthened by being provided with ribs 4, as a part thereof, extending throughout the length of the caps along the 70 middle of the underside, and uniting them with the body portion 1.

In order to still further strengthen the grate bar construction, the ribs 4 and 5 are 75 preferably connected by a plurality of transverse partitions 14, which, in the present instance, are uniformly spaced apart, longitudinally of the ribs 4 and 5, substantially as indicated in Fig. 3. The transverse partitions 14, as will be seen more particularly in 80 Fig. 4, divide the vertical-horizontal air passages 9-10 into a plurality of air passages entering the continuous channels or air passages 7 between the caps 6. It will be observed that the transverse partitions 14 do 85 not extend across the longitudinal channels 7, between the caps 6, thereby leaving this channel continuous, as previously indicated. Preferably, the side walls of the continuous longitudinal channels 7, are beveled or flared 90 outwardly, as will be seen in Figs. 1 and 4, to facilitate the entrance of air into the fine coal that may be spread over the caps of the grate bar. As shown at 15 in Fig. 4, it will 95 be seen that alternate ribs 5 are preferably made wider or extend below the other ribs, in order to further strengthen and brace the 100 grate bar.

By the construction shown, it will be seen 105 that the vertical-horizontal air passages 9-10, under the respective elongated caps 6 are completely separated by the mid-rib 4, so that there can be no confusion of air under the caps. In that two separate passages are provided, the air entering the channels or air passages 7 between the caps, which comes from below the grate bar, passes 110 through individual air passages 9-10, which, as previously pointed out, are preferably divided into a plurality of passages by the transverse partitions 14. Furthermore, it 115 will be understood that, in providing the caps 6 with the ribs 4, depending from the middle thereof, and connecting these by the transverse partitions 14, which are cast integral with the caps 6 and with the ribs 5, as shown in Fig. 4, a particularly rigid construction is provided. Therefore, the caps 120 may be subjected to considerable abuse, in the way of extremes of or variable temperatures 125 without the caps or grate bars becoming seriously damaged. In view of the fact that many boilers and furnaces, at times, may not be properly fired, this feature is of particular importance.

The operation of my improved grate bar is comparatively simple and should be readily understood from the description given. It will be understood that when the fine coal is spread over the caps 6, a portion thereof will bridge and partially fill the channels 7 therebetween, and the air coming up through the individual vertical-horizontal air passage 9-10 will enter the continuous longitudinal channel 7, to provide the necessary air for combustion of the coal. It has been found in practice that my improved grate bars operate efficiently and satisfactorily, in supplying the necessary air, while at the same time being capable of withstanding the destructive effects of high and variable temperatures.

While I have illustrated a single relatively small section of my improved grate bar, it will be understood that grate bars of any length and width may be used and the longitudinal caps 6 may be formed of any length desired, and while, for the purpose of illustration, only four such caps are represented, it will be understood that any desired or required number may be provided. Furthermore, it will be understood that while I have shown only one form and arrangement of my improved grate bar, I do not wish to be limited to the specific details of construction shown and described, for these may be varied according to requirements, without departing from the spirit and scope of the invention.

I claim:—

1. A grate bar section, comprising a rectangular frame cast integral with a plurality of relatively long parallel ribs, spaced from each other laterally to form continuous channels therebetween, said ribs being T-shaped in cross section, the flanges of adjacent ribs being on different levels and arranged so that the flanges of the ribs on the upper level extend beyond the edges of the flanges of the ribs on the lower level and over the sides of said frame but are spaced therefrom, so as to provide vertically then horizontally extending air passages therebetween, and lugs on the sides of said frame for supporting the individual grate bar section.

2. The grate bar section as claimed in claim 1, in which transverse partitions in spaced relation longitudinally of said T-ribs connect said ribs and the sides of said frames and are adapted to divide said vertical-horizontal air passage into a plurality of separate tubular passages.

3. A grate bar section, comprising a rectangular body portion cast integrally with a plurality of laterally spaced parallel ribs of T-shaped cross-section extending the length of said body portion and arranged on two levels, alternate ribs being on the upper level and provided with lateral flanges, forming elongated caps overlapping the ribs on the lower level, the sides of said body portion serving as boundary ribs on the lower

level, and a plurality of transverse partitions cast integral with said ribs and the sides of said body portion in spaced relation longitudinally thereof to form a plurality of tubular air passages under said caps and between said ribs, said transverse partitions not extending across the opening between the lateral flanges on the upper level ribs, thereby leaving continuous longitudinal channels therebetween.

4. The grate bar section as claimed in claim 3, in which the ribs alternating with said cap ribs and located on the lower level are provided with lateral flanges, the upper surfaces of which incline downward from and on each side of the middle of the ribs.

5. A grate bar section comprising a rectangular body portion cast integrally with a plurality of T-shaped parallel ribs arranged on two levels, the sides of said frame serving as boundary ribs on the lower level, said ribs being spaced apart laterally to form vertical air passages therebetween, the T-head lateral flanges on the upper level being adapted to form caps overlapping the flanges of the lower level ribs, including said side frame boundary ribs, but spaced vertically therefrom to leave lateral passages continuous with said vertical passages, said cap flanges being spaced apart laterally to leave continuous unobstructed longitudinal channels therebetween into which said vertical-lateral passages enter.

6. The grate bar section as claimed in claim 5, in which said vertical-lateral passages are divided by a plurality of transverse partitions extending between said ribs and the sides of said frame to form separate tubular passages leading into the continuous longitudinal channels between said T-shaped cap flanges.

7. A grate bar section comprising a body portion of rectangular shape, cast integrally with a plurality of continuous caps extending longitudinally thereof and spaced apart transversely to form upwardly opening continuous channels therebetween, and a plurality of tubular air passages formed below said caps extending vertically then horizontally and opening laterally into the respective continuous channels between said caps, said tubular air passages being defined by ribs below said caps, and transverse partitions between said ribs and the sides of said body portion.

8. The grate bar section as claimed in claim 7, in which the bottoms of said continuous channels between the caps slope in opposite directions from the middle of the respective passages, and said vertical-horizontal air passages under the caps cooperate with said sloping bottoms in directing air into said continuous channels between said caps.
